(57) **CLAIM**

The ornamental design for a lock for a disc storage hub, as shown and described.

DESCRIPTION

FIG. 1 is a perspective view of a first embodiment of the lock for a disc storage hub showing our new design;

FIG. 2 is a top plan view of FIG. 1;

FIG. 3 is a bottom plan view of FIG. 1;

FIG. 4 is a left side elevation view of FIG. 1; the right side elevation being a mirror image thereof;

FIG. 5 is a front elevation view of FIG. 1;

FIG. 6 is a rear elevation view of FIG. 1;

FIG. 7 is a perspective view of a second embodiment of the lock for a disc storage hub showing our new design;

FIG. 8 is a top plan view of FIG. 7;

FIG. 9 is a bottom plan view of FIG. 7;

FIG. 10 is a left side elevation view of FIG. 7; the right side elevation being a mirror image thereof;

FIG. 11 is a front elevation view of FIG. 7; and,

FIG. 12 is a rear elevation view of FIG. 7.
